(57) **CLAIM**

The ornamental design for a rally cap, as shown and described.

DESCRIPTION

FIG. 1 is a front perspective view of a rally cap according to the present invention;

FIG. 2 is a rear perspective view of the rally cap according to the present invention as shown in FIG. 1 with the closure device in an open position;

FIG. 3 is a front elevation view of the rally cap according to the present invention as shown in FIG. 1;

FIG. 4 is a rear elevation view of the rally cap according to the present invention as shown in FIG. 1 with the closure device in an open position;

FIG. 5 is a side elevation view of the rally cap according to the present invention as shown in FIG. 1;

FIG. 6 is a side elevation view of the rally cap according to the present invention as shown in FIG. 1, shown from the opposing side view as that shown in FIG. 5;

FIG. 7 is a top plan view of the rally cap according to the present invention as shown in FIG. 1 with the closure device in an open position;

FIG. 8 is a bottom plan view of the rally cap according to the present invention as shown in FIG. 1 with the closure device in an open position;

FIG. 9 is a rear perspective view of the rally cap according to the present invention as shown in FIG. 1 with the closure device in a closed position; and,

FIG. 10 is a bottom plan view of the rally cap according to the present invention as shown in FIG. 1 with the closure device in a closed position;

The portions shown in broken lines illustrate environment and form no part of the claimed design.

1 Claim, 5 Drawing Sheets
